(57) **CLAIM**

The ornamental design for a replaceable blade for weed cutters, as shown and described.

DESCRIPTION

FIG. 1 is a left view showing a replaceable blade for weed cutters according to a first embodiment of the present invention;

FIG. 2 is a top plan view showing the replaceable blade of FIG. 1, the bottom plan view being identical;

FIG. 3 is a right view showing the replaceable blade of FIG. 1;

FIG. 4 is a front view showing the replaceable blade of FIG. 1, the rear view being a mirror image thereof;

FIG. 5 is a rear view showing a replaceable blade for weed cutters according to a second embodiment of the present invention;

FIG. 6 is a left view showing the replaceable blade of FIG. 5;

FIG. 7 is a top plan view showing the replaceable blade of FIG. 5, the bottom plan view being a mirror image thereof;

FIG. 8 is a right view showing the replaceable blade of FIG. 5;

FIG. 9 is a front view showing the replaceable blade of FIG. 5;

FIG. 10 is a left view showing a replaceable blade for weed cutters according to a third embodiment;

FIG. 11 is a top plan view showing the replaceable blade of FIG. 10, the bottom plan view being identical;

FIG. 12 is a right view showing the replaceable blade of FIG. 10;

FIG. 13 is a front view showing the replaceable blade of FIG. 10, the rear view being a mirror image thereof; and, FIG. 14 shows a replaceable blade in its intended use with the broken lines being for illustrative purposes only and forming no part of the claimed design.
